UNITED STATES PATENT OFFICE.

ALBERT B. HERRICK, OF NEW YORK, N. Y., ASSIGNOR TO MATIE C. MESSLER, OF PAWTUCKET, RHODE ISLAND.

IGNITER.

1,112,795.

Specification of Letters Patent.

Patented Oct. 6, 1914.

Application filed November 30, 1912. Serial No. 734,343.

To all whom it may concern:

Be it known that I, ALBERT B. HERRICK, a citizen of the United States, and a resident of New York, county of New York, 5 and State of New York, have invented a new and useful Improvement in Igniters, (Case C,) of which the following is a specification, the principle of the invention being herein explained and the best mode in 10 which I have contemplated applying that principle, so as to distinguish it from other inventions.

The subject of the present invention is a new and improved induction coil which is 15 particularly adapted for use in an igniter.

The device consists, in general terms, of a plurality of magnets, a plurality of induction coils and means for reversing the direction of the magnetic flux through the induction coils.

In particular, the device consists of a plurality of induction coils, a plurality of magnets and an armature which normally connects up each of the magnets with one of the 25 induction coils, thus forming two separate closed circuits. The magnets, the coils and the armature are so formed that when the armature is operated it breaks the two circuits previously formed and connects up 30 each of the magnets with the coil with which it was not previously in circuit. Furthermore, the magnets are so disposed that the shifting of the circuits produces a reversal 35 of the direction of the magnetic flux in each coil.

The device is particularly adapted for use in gas engines to take the place of the present spark plug and magneto or battery. It is self-contained and is automatically operated by the compression in the engine cylinder. The device is not limited to the adaptation here described, and other uses will readily suggest themselves to one skilled 40 in the art.

The annexed drawings and the following description set forth in detail certain mechanism embodying the invention, such disclosed means constituting, however, but one of various mechanical forms in which the 45 principle of the invention may be used.

In said annexed drawings:—Figure 1 is a central vertical section through my device as constructed with a spark plug; Fig. 2 is a plan view showing the coils and the magnets; Fig. 3 is a plan view of the casing 55 showing the means for advancing the spark and for manually operating the mechanism; Fig. 4 is a view in perspective of the preferred form of armature; Fig. 5 is a section on the line 5—5 in Fig. 2, showing also the 60 position of the armature when in its lower position; Fig. 6 is a view on the line 6—6 in Fig. 2 showing the armature in its upper position; and Fig. 7 is a diagrammatic view illustrating the electrical connections. 65

In Fig. 1 there is shown a spark plug 1 which is threaded at 2 adapting it to enter the usual aperture in the cylinder of an internal combustion engine. The spark plug is extended radially outward thus forming a 70 chamber 3 and a flange 4. Upon the flange 4 there is suitably mounted a base 5 upon which will be mounted the magnets and the induction coils. Between the base member 5 and the flange 4 there is mounted a dia- 75 phragm 6 which is attached to a rod 7 at- tached to an armature member 8, the rod 7 extending through the chamber 3 and be- ing provided with a terminal 9 which is 80 adapted to coöperate with a terminal 10 at- tached to the spark plug proper. The ter- 85 minals 9 and 10 correspond to the usual spark plug terminals as will be readily seen. The rod 7 is made up of an insulating ma- terial, surrounding the wire (not shown), 90 which connects the terminal 9 with the in- duction coil, and a metal sleeve surround- ing the insulating material which is preferably porcelain, for the purpose of strengthening it and giving greater rigidity. Upon the 95 base member 5 there are mounted two pre- ferably laminated magnets 11 and 12 and two induction coils 13 and 14. Each induction coil consists of a soft iron core 15, consist- 95 ing of a number of short plates of iron wire provided at either end with plates 16 and 17, and a high tension secondary coil 19.

The construction of the armature is shown in Fig. 4, and it will be seen that it consists of a central rod 8, at either end of which 100

there are attached keepers 20, 21, 22 and 23, each keeper having its two ends magnetically insulated from the other by the interposition of brass strips 80. Similarly each keeper is insulated from the adjacent transversely disposed keeper. For convenience the keepers will be referred to as consisting of only one member since the two ends of each operate in the same manner. The 10 keepers are formed as shown with beveled faces adapted to contact with complementary contact faces formed on the magnets and plates attached to the coils.

Referring to Fig. 2 it will be noticed that 15 the top of the coil 13 is provided with a downwardly beveled contact face 24 and with an upwardly beveled contact face 25. Similarly the adjacent magnet 12 is formed with a contact face 26 corresponding to the 20 contact face 24 of the coil, and adjacent thereto, and with a contact face 27 corresponding to the contact face 25 on the coil. The magnets 11 and 14 are formed with contact faces 28, 29, 30 and 31, which are disposed as are the contact faces on the other magnet and coil. The contact faces which are formed on the magnets and coils are identical for the top and bottom portions, that is, for each contact face shown in Fig. 25 30 there will be a similarly disposed, and parallel contact face on the bottom of the coil or magnet. The magnets and coils are disposed in a quadrilateral as shown in Fig. 2, the magnets being disposed diagonally 35 opposite each other and having their magnetically opposite poles disposed adjacent each other, that is, the north pole of the magnet 11 will be at the top of the same, as indicated by the letter N, and the south 40 pole of the magnet 12 will be at the top, as indicated by the letter S, thus being adjacent the north pole of the magnet 11, reducing to a minimum the leakage from the magnets. The relative disposition of magnets 45 and coils is a matter of small importance, as the armature can be constructed to suitably coöperate with practically any desired arrangement of coils and magnets, the present arrangement being preferred by reason 50 of its simplicity.

When the armature is in the position shown in Fig. 5, that is its normal or lower position, the keepers 21 will engage the contact faces 24 and 26 on the coil 13 and the 55 magnet 12. This will produce a magnetic flux through the induction coil 13 in a clockwise direction when looking at the magnet and coil from the viewpoint taken in Fig. 5. Also the keeper 23 will similarly connect the 60 lower contact faces on the coil 13 and the magnet 12, since the contact faces at the bottom of these parts are parallel with the upper correspondingly disposed faces. Similarly, the other ends of the keepers 21 and 23 65 will engage the contact faces 29 and 30 on

the magnet 11 and the coil 14, and the corresponding faces on the bottom of these members, thus producing a second closed magnetic circuit, the direction of the magnetic flux being through the coil 14 in a 70 clockwise direction. An electrical current is thus induced in the coil 14 and in the coil 13.

Upon raising the armature the keepers 21 and 23 are removed from engagement with the contacts 24, 26, 29 and 30, thus breaking 75 the magnetic circuits which have previously been described. Simultaneously with the breaking of these circuits, or substantially so, new magnetic circuits will be formed by means of the keepers 20 and 22, the keeper 80 20 engaging the contacts 25 and 28 on the coil 13 and the magnet 11, respectively, and the contacts 27 and 30 on the magnet 12 and the coil 14, respectively. In this way two new closed magnetic circuits are formed, the 85 direction of the magnetic flux being in a clockwise direction when looking at the coil and magnet from the viewpoint taken in Fig. 6. This reverses the direction of the magnetic flux through the coil 13. Similarly a new magnetic circuit is formed 90 through the magnet 12 and the coil 14, the direction of the flux being parallel to that in the previously described circuit, thus also reversing the direction of the magnetic flux 95 through the coil 14. By breaking the circuits in four places a very fast breaking speed is secured, and by reversing the direction of the magnetic flux through the coils at the same instant a very hot spark is produced at the terminals of the spark plug, 100 since the induced current varies from a positive maximum to a negative maximum.

About the coils and magnets I dispose a suitable aluminum casing 40 which is attached to the base member 5 and is provided with a central aperture on its top in which I introduce a sleeve 41 provided with an inwardly extending shoulder 42. The sleeve 41 is held in position by means of a cap 43 105 which screws onto the same, but will not enter the aperture on the casing. Slidably disposed in the sleeve 41 is a rod 44 which is provided with a head or shoulder 45 110 adapted to slide in the sleeve but of a sufficient diameter to prevent its passing the shoulder 42. Attached to the sleeve 41 is a cam member 46 bearing against a spring 47 115 disposed about the rod 44 and resting upon a disk 48 which is threaded for adjustment 120 on the rod 44 to which it may be pinned as shown. The rod 44 is threaded at its lower end thus adapting it to engage an aperture in the top of the armature 8. By adjusting the disk on the rod 44 at the proper position 125 the tension on the spring 47 can be adjusted to cause the armature to operate at the desired compression. By means of the spring 47 and the cam 46 it is possible to adjust the mechanism to correspond to slight changes 130

in the compression in the engine cylinder. The diaphragm 6 is of course designed to operate rapidly at a given pressure, but is not sufficiently rigid to withstand the combustion pressure in the cylinder. By rotating the sleeve 41 the cam 46 is rotated, thus forcing down the spring 47 and increasing the pressure against the disk 48. This pressure is of course transmitted to the diaphragm 10 through the armature 8 and the rod 7. Pivotally attached to a lug 50 on the cap 43 is a lever 51 provided with a handle 52 and terminating in a tooth 53 engaging a semi-circular rack 54 mounted on the top of the 15 casing. When it is desired to vary the pressure on the diaphragm the handle 52 is rotated, it first being depressed at its right end, thus disengaging the tooth 53 from the rack. When the desired pressure is secured 20 the handle 52 is returned to its normal position, the tooth 53 then engaging the rack and holding the handle from further movement, thus locking the cam 46 and maintaining the desired pressure. A spring 55 is attached to 25 the lever and to the cap 43 and tends to retain the lever in engagement with the rack. When it is desired to operate the mechanism in order to start the engine the handle 52 is raised, this action raising the sleeve 41, 30 the shoulder 42 on this sleeve engaging the head 45 thus raising the rod 44 and the armature 8. Since the disk 45 can slide freely within the tube 41, the latter is not moved by the automatic operation of the 35 device.

In the base member 5 I provide a soft metal pad or backing for the diaphragm 6. The diaphragm is first raised into its upper or operated position, the metal then being 40 poured against the diaphragm within the base member 5. The backing is thus made to conform to the diaphragm, but will not in any case interfere with the operation of the diaphragm, as the latter does not engage the 45 pad until it has operated. When operated, however, it is forced against the pad which takes up the great pressure which is produced in the engine cylinder at the time of firing. Suitable means for cooling the pad 50 may be provided, such for example as apertures 56 in the base 5.

My invention can be applied to either high or low tension ignition, the form of the coils varying with the desired ignition, but in the 55 present form I have merely shown two high tension secondary coils, as a very hot spark can be secured with such mechanism. A condenser 57 is preferably included in the circuit being connected across the lead wires 58 and 59 from the two secondary coils as shown in Fig. 7. The construction of the condenser is not of primary importance as any suitable type may be used, but I preferably employ two insulated metal sheets 60 65 and 61 extending around the coils and mag-

nets inside of the casing, the two sheets being insulated by suitable material such as micanite 62.

The features to which I wish to call special attention in my invention are the plurality of magnets and coils providing for a plurality of magnetic circuits, and the construction and disposition of the contact bars on the magnets, coils and armature, these several features making it possible to secure 75 a very intense and rapid spark with a very slight travel of the armature and with but slight loss from those sources which usually detract from the efficiency of induction coils of other makes. These features render the 80 invention particularly well suited to use as an igniter, although this is but one of the uses to which it may be put.

Other modes of applying the principle of my invention may be employed instead of 85 the one explained, changes being made as regards the mechanism herein disclosed, provided the means stated by any of the following claims or the equivalent of such stated means be employed.

I therefore particularly point out and distinctly claim as my invention:—

1. The combination of a spark plug adapted to enter an aperture in an engine cylinder; two magnets and two induction coils 95 attached to said spark plug and arranged symmetrically thereon, said coils being connected to the terminals of said spark plug; a movable member mounted in said spark plug and adapted to be operated by the compression in the engine cylinder; an armature attached to said movable member, said armature being adapted, in the normal position of said member, to connect up said magnets and said coils in two separate magnetic circuits, 105 said armature, when said member is operated, being adapted to connect up each of said magnets with the coil formerly in magnetic circuit with the other magnet, thereby reversing the direction of the magnetic flux 110 through said coils.

2. The combination of a hollow spark plug adapted to enter an aperture in an engine cylinder; a magnet and an induction coil co-operatively mounted on said spark plug, an armature reciprocably mounted to co-operate with said magnet and induction coil; and a flexible diaphragm mounted in said hollow spark plug and connected to said armature to operate the same, said diaphragm being operable by the compression in the engine cylinder.

3. The combination of a hollow spark plug adapted to enter an aperture in an engine cylinder; a magnet and an induction coil co-operatively mounted on said spark plug, an armature reciprocably mounted to co-operate with said magnet and induction coil; and a flexible diaphragm mounted in said hollow spark plug and connected to 130

said armature to operate the same, said diaphragm being operable by the compression in the engine cylinder; and a suitable support adapted to contact said diaphragm when operated.

4. The combination of a hollow spark plug adapted to enter an aperture in an engine cylinder; a magnet and an induction coil co-operatively mounted on said spark plug, an armature reciprocably mounted to co-operate with said magnet and induction coil; and a flexible diaphragm mounted in said hollow spark plug and connected to said armature to operate the same, said diaphragm being operable by the compression in the engine cylinder; and a soft metal support adapted to contact said diaphragm when operated to support the same against the combustion pressure in said cylinder.

10

15

20 5. The combination of a hollow spark
plug adapted to enter an aperture in an en-
gine cylinder; a magnet mounted on said
plug; an induction coil mounted on said
plug; an armature reciprocably mounted
25 between said magnet and coil, and normally
connecting the same in a closed magnetic
circuit, said armature when operated, being
adapted to vary the magnetic circuit be-
tween said coil and magnet, thereby induc-
30 ing a current in said coil; a movable mem-
ber mounted in said hollow spark plug and
adapted to be operated by the compression
in the engine cylinder, said member being
connected to said armature to operate the
35 same; and tension means adapted to con-
trol said movable member, whereby the lat-
ter will operate when a predetermined com-
pression is reached.

6. The combination of a hollow spark
40 plug adapted to enter an aperture in an engine cylinder; a magnet mounted on said plug; an induction coil mounted on said plug; an armature reciprocably mounted between said magnet and coil, and normally
45 connecting the same in a closed magnetic circuit, said armature when operated being adapted to vary the magnetic circuit between said coil and magnet, thereby inducing a current in said coil; a diaphragm
50 mounted in said hollow spark plug and adapted to be operated by the compression in the engine cylinder, said diaphragm being connected to said armature to operate the same; and tension means adapted to
55 control said diaphragm whereby the latter will operate when a predetermined compression is reached.

7. The combination of a hollow spark plug adapted to enter an aperture in an engine cylinder; a magnet mounted on said plug; an induction coil mounted on said plug; an armature reciprocably mounted between said magnet and coil, and normally connecting the same in a closed magnetic circuit, said armature when operated being

adapted to vary the magnetic circuit between said coil and magnet, thereby inducing a current in said coil; a diaphragm mounted in said hollow spark plug and adapted to be operated by the compression in the engine cylinder, said diaphragm being connected to said armature to operate the same; and adjustable tension means adapted to control said diaphragm whereby the latter will operate when a predetermined compression is reached. 70 75

8. The combination of a hollow spark plug adapted to enter an aperture in an engine cylinder; a magnet mounted on said plug; an induction coil mounted on said plug; an armature reciprocably mounted between said magnet and coil, and normally connecting the same in a closed magnetic circuit, said armature when operated being adapted to vary the magnetic circuit between said coil and magnet, thereby inducing a current in said coil; a diaphragm mounted in said hollow spark plug and adapted to be operated by the compression in the engine cylinder, said diaphragm being connected to said armature to operate the same; a rod attached to said armature; a disk attached to said rod; resilient means bearing against said disk; and means adapted to vary the tension on said resilient means. 80 85 90 95

9. The combination of a hollow spark plug adapted to enter an aperture in an engine cylinder; a magnet mounted on said plug; an induction coil mounted on said plug; an armature reciprocably mounted between said magnet and coil, and normally connecting the same in a closed magnetic circuit, said armature when operated being adapted to vary the magnetic circuit between said coil and magnet, thereby inducing a current in said coil; a diaphragm mounted in said hollow spark plug and adapted to be operated by the compression in the engine cylinder, said diaphragm being connected to said armature to operate the same; a rod attached to said armature; a disk attached to said rod; a coiled spring disposed about said rod against said disk; a sleeve rotatably mounted on said rod; a cam attached to said sleeve and bearing against said spring, whereby rotation of said sleeve will vary the tension on said spring. 100 105 110 115

10. The combination of a hollow spark plug adapted to enter an aperture in an engine cylinder; a magnet mounted on said plug; an induction coil mounted on said plug; an armature reciprocably mounted between said magnet and coil, and normally connecting the same in a closed magnetic circuit, said armature when operated being adapted to vary the magnetic circuit between said coil and magnet, thereby inducing a current in said coil; a diaphragm 130

and said cam whereby rotation of said sleeve varies the pressure on said diaphragm; a semicircular rack mounted on said casing; a toothed lever pivotally attached to said sleeve and engaging said rack; and a spring normally retaining said lever in engagement with said rack.

Signed by me this 21st day of November, 1912.
